HORIZONTAL FLUTED PUSH BAR

James L. Fountain, P.O. Box 30218, Dallas, Tex.

Filed June 24, 1963, Ser. No. 75,486

Term of patent 14 years

(Cl. D10—8)

FIG. 2

FIG. 1

FIG. 3

FIG. 1 is a perspective view of the push bar;
FIG. 2 is a top view of the push bar with a portion of
the bar broken away for convenience of illustration; and
FIG. 3 is an end view of the push bar.
I claim:
The ornamental design for a horizontal fluted push bar,
as shown and described.
